UNITED STATES PATENT OFFICE.

JOHN A. LAMONT, OF CHICAGO, ILLINOIS, ASSIGNOR TO AMERICAN STEEL FOUNDRIES,
OF CHICAGO, ILLINOIS, A CORPORATION OF NEW JERSEY.

TRUCK SIDE FRAME.

Continuation of application Serial No. 433,412, filed December 27, 1920. Now Patent No. 1,377,704, dated May 10, 1921. This application filed April 18, 1921, Serial No. 462,179.

To all whom it may concern:

Be it known that I, JOHN A. LAMONT, a citizen of the United States, residing at Chicago, in the county of Cook and State of Illinois, have invented certain new and useful Improvements in Truck Side Frames, of which the following is a specification.

This invention relates to a truck side frame and more particularly to a side frame 10 for a six-wheel truck.

This application is a continuation of applicant's co-pending application, Serial No. 433,412 filed December 27, 1920.

The object of this invention is to provide 15 a truck side frame which is simple, relatively light, and yet durable in construction, and having a plurality of portions adapted to cooperate with journal boxes, bolster members, equalizing members, etc., in a 20 manner to meet all the requirements for successful commercial operation.

This and other objects are accomplished by means of the arrangement disclosed on the accompanying sheet of drawings in 25 which—

Figure 1 is a side elevation of a truck side frame embodying my invention;

Figure 2 is a fragmentary top plan view of the same side frame;

Figure 3 is a fragmentary bottom plan view of said side frame;

Figure 4 is a fragmentary view showing an inside elevation of the side frame at one of the bolster openings; and,

Figures 5, 6, 7, 8 and 9 are respectively 30 sectional views taken in the planes of lines 5—5, 6—6, 7—7, 8—8 and 9—9 of Figure 1.

The various novel features of my invention will be apparent from the following 40 description and drawings and will be particularly pointed out in the appended claims.

Referring to the figures of the drawings, it will be noted that I have disclosed my invention in connection with a six-wheel 45 truck side frame cast in a single piece and forming a beam 10. This side frame is provided with a middle pocket 11, for the reception of intermediate journal box and equalizer parts and with two other pockets 50 12 intermediate said middle pocket 11 and the end of the frame for receiving end journal boxes. The middle pocket 11, has side walls 13, by means of which the associated middle journal box is guided in its relative

vertical movement. This middle pocket 11, 55 also has side walls 14 for limiting relative lateral movement between the middle journal box and the side frame. As shown, the side walls 14 are provided with ribs 15 for increasing the strength of the section at this 60 point. By referring particularly to Figure 8 it will be noted that the side frame at the section in question is channel shaped and is narrower at the top than at the intermediate and lower portions of the side 65 frame, upwardly converging portions 16 connecting the wider and narrower parts of the side frame at this section.

Each of the pockets 12 for receiving end journal boxes has downwardly extending 70 walls 17 for guiding the associated journal boxes in their relative vertical movement with respect thereto. The roof of each of the pockets 12 is provided with a recess 18 for the reception of a rib formed on the 75 upper surface of the associated journal box. Formed integrally with the guide wall 17 and on one side thereof are walls 27 depending from the main portion of the side frame and being circular in plan, as shown particularly in Figures 2 and 3 for the reception 80 of springs which are interposed between the side frame and associated journal boxes. The depth of these spring pockets 27, increases toward the guide wall 17 of 85 the pockets 12 and are formed to retain the springs in question. In the roof of these spring pockets, downwardly extending lugs 19 are formed for centering the springs.

Intermediate the middle pocket 11 and 90 each of the end pockets 12 are pockets 20 for bolster members. In this particular instance, the pockets extend upwardly within the side frames and have side walls 21 which act as vertical guides for the bolster ends 95 and also cooperate with the bolster members for taking all thrusts and shocks incident to starting and stopping of the car. The pockets also have end walls 25 for increasing the strength of the section. Intermediate 100 each bolster pocket 20 and the adjacent end pocket 12 is a depending portion 22 terminating in a bearing 23 formed by drilling an opening 24 for the reception of a pin 26 which pivotally supports one end of an associated equalizing lever.

This single piece integrally formed side frame is shown quite generally in channel

and in box sections throughout its length but it will be understood that the sections may be varied at different points without departing from the spirit of the scope of the invention.

5. It is my invention to cover all modifications falling within the terms of the following claims.

I claim:

1. An integrally formed side frame for a 10 six-wheel truck having formed therein pockets for intermediate and end journal boxes and having depending wall portions forming pockets for the reception of springs at the sides of associated journal boxes.

15. 2. An integrally formed truck side frame having formed therein pockets for journal boxes and having depending wall portions forming pockets for the reception of springs at the sides of associated journal boxes.

20. 3. An integrally formed side frame for a six-wheel truck having formed therein pockets for intermediate and end journal boxes and having depending wall portions forming pockets for the reception of springs 25 at the sides of associated journal boxes, said side frame also having supporting means for an equalizing lever.

4. An integrally formed side frame for a six-wheel truck having formed therein

pockets for intermediate and end journal boxes and for bolster members and having depending wall portions forming pockets for the reception of springs at the sides of associated journal boxes.

5. An integrally formed side frame for a 35 six-wheel truck having formed therein pockets for intermediate and end journal boxes and for bolster members and having depending wall portions forming pockets for the reception of springs at the sides of associated journal boxes, said side frame also having supporting means for an equalizing lever.

6. An integrally formed side frame for a six-wheel truck having formed therein 45 pockets for intermediate and end journal boxes and pockets for bolster members and also having downwardly extending portions intermediate the end journal box pockets and bolster member pockets forming a support for equalizing levers, said downwardly extending portions extending downwardly to form the lowest parts of the side frame to permit the use of equalizing levers substantially longitudinal throughout their lengths. 50 55

Signed at Chicago, Illinois, this 14th day of April, 1921.

JOHN A. LAMONT.
